UNITED STATES PATENT OFFICE

158,823

GAME BOARD

William J. Weir, Miami, Fla.

Application August 4, 1949, Serial No. 4,307

Term of patent 14 years

(Cl. D34—5)

To all whom it may concern:

Be it known that I, William J. Weir, a citizen of the United States, residing at Miami, county of Dade, and State of Florida, have invented a new, original, and ornamental Design for a Game Board, of which the following is a specification, reference being had to the accompanying drawing, forming a part thereof, and is a continuation in part of my co-pending application, Serial No. D. 137,373, filed March 5, 1947, which has become abandoned.

The drawing has been shaded to show contrasting appearance.

The dominant features of my new design are shown in solid lines in the drawing. The back of the game board is plain and unornamented.

I claim:

The ornamental design for a game board, as shown and described.

WILLIAM J. WEIR.
